CONTROL SYSTEM

Phillips Thomas, Edgewood, Pa., assignor to Westinghouse Electric & Manufacturing Company, a corporation of Pennsylvania

Application August 14, 1929, Serial No. 385,915

8 Claims. (Cl. 177—337)

My invention relates to control systems and has particular relation to traffic-control systems.

The so-called "program" traffic-control systems known to the art include a controller and a motor 5 for driving the same, electrically arranged to energize sets of signal lights or stop and go traffic indications on two or more intersecting highways to permit the traffic on alternate highways to proceed.

As the terms "stop indications" and "go indications" are used hereinafter, they are assumed to mean any type of manifestation that indicates to traffic how it shall proceed. While such indication is ordinarily a visual manifestation such as a 15 signal light of a particular color, it may take other forms and traffic may in certain systems be restrained or be permitted to pass by the absence of any signal at all. The absence of a signal in such a case is of course also an "indication" as the 20 word is used here.

These systems are satisfactory when there is a uniform volume of traffic of about equal proportions on each highway throughout the 24 hours of the day, but this condition seldom occurs in 25 practice, so that, oftentimes, it is necessary for a vehicle on one highway to come to a stop and wait during the change of signals, although no vehicles are present on the intersecting highway, thus resulting in loss of time and additional traffic 30 congestion.

My invention is intended to obviate these and other difficulties and, therefore, it is an object of my invention to provide a control system which will permit traffic to flow uninterruptedly along 35 one of a number of intersecting highways but which will function on the approach of a vehicle on one of the intersecting highways to cause the traffic signal to go through a given sequence of signals.

Another object of my invention is to provide a 40 device so arranged that, on failure of the actuating circuits, the control is transferred to a "program" control system.

Another object of my invention is to provide 45 means whereby vehicles on a main highway may cause the traffic signal to be energized in a given sequence of signals to permit the vehicle to make a left-hand turn across the highway.

Other objects of my invention will become 50 apparent in the following description of my invention taken in conjunction with the drawing.

Referring to the drawing, in which like figures indicate like parts,

Figure 1 is a schematic diagram of my traffic- 55 control system, as applied to the intersection of

two highways, with the highways and traffic-control-system devices shown generally only, and

Fig. 2 is a view, partly in elevation and partly in section, of one of the highways showing portions of the traffic-control system installed thereon. 5

In practicing my invention, I provide light-sensitive cells mounted in or adjacent to the traffic lanes and to the left-hand-turn lane in such manner that, on approach of a vehicle on any of 10 the lanes, the traffic signal is caused to go through a given sequence of "stop", "caution" and "go" signals to permit vehicles on the left-hand-turn lanes or on the auxiliary lanes to enter into or cross the main highway. 15

Referring more particularly to Fig. 2 of the drawing, a light-sensitive cell C is disposed within a recess in a highway in such manner that daylight or an artificial light source, such as the lamp 1, suspended above the highway, maintains 20 the light-sensitive device in an energized condition, but, on the approach of a vehicle V, the light falling on the cell from the light source is interrupted and the light-sensitive cell is deenergized, causing a cooperating electromagnetic relay to 25 drop to its deenergized position, thereby closing an electrical circuit hereinafter described, to actuate the traffic signals.

If desired, a light-sensitive device C1 may be 30 utilized for deenergizing the light source 1 during the day time and sun-light may be utilized for operating the light-sensitive cell. The light-sensitive cell C may be disposed in a recess in the highway, as shown, or may be disposed on a standard 2 at the side of the highway, with a 35 light source mounted on the other side of the traffic lane, or the light-sensitive device may be disposed above the highway, with the light source mounted below the highway.

Referring more particularly to Fig. 1, which 40 shows the intersection of a major or main highway M and a minor or auxiliary highway A, the light-sensitive cells CN and CS are disposed in the traffic lanes to the right of the center of the auxiliary highway adjacent to the intersection, 45 so that a vehicle approaching the intersection passes in close proximity to the light-sensitive device. The passage of the vehicle interrupts the light beam impinging upon one of the cells and causes one of the coating relays RN and RS to 50 become deenergized to break an electrical circuit hereinafter described.

Other light-sensitive cells, such as the cell CL, 55 may be disposed in a left-hand-turn lane of the main highway, and relays, such as the relay RL,

associated therewith, may be utilized to control the signal to permit a vehicle to make a left-hand-turn across the main highway.

5 Electrical energy for energizing the traffic-control system is furnished by means of main-line conductors L1 and L2. The relay control devices, which, in the present instance, comprise a light-sensitive cell C and a grid glow tube T, are disposed in series electrical relation with respect to 10 their respective relays and in parallel electrical relation with each other.

15 Any suitable light-sensitive device may be utilized, but the light-sensitive device C here shown comprises a tube having an anode 3 and a cathode 4. When light impinges upon the cell, a discharge takes place between the anode and the cathode. The control electrode 5 of the grid-glow tube T is connected in parallel electrical relation to the cathode 4 of the light-sensitive cell 20 C and, so long as the potential of the control electrode 5 is approximately the same as that of the anode of the grid-glow tube, a discharge takes place between the anode and the cathode of the grid-glow tube. Control of the voltage at the 25 terminals of the light-sensitive cell and the grid-glow tube and tuning of the circuit is effected by means of a rheostat 6 and a capacitance 7.

30 Any traffic signal known to the art may be utilized by a suitable modification of the electrical connections, but the traffic control signal, here shown, comprises three signal boxes disposed one above another. One signal lamp MG is adapted to display a green or "go" signal on the main highway and a red or "stop" signal on the side highway, when energized. Another signal Y is 35 disposed to display a yellow or "caution" signal on both highways, and the third signal MR is arranged to show a red or "stop" signal on the main highway and a green or "go" signal on the 40 side highway.

45 The signals may be caused to be actuated in sequence by means of a program controller PC driven by a program-controller motor PCM. The signal controller 11 of the program controller includes four sectors adapted to control and energize the three signal lights, as hereinafter described. A second controller disc 8, provided with a single insulated sector 27 of conducting material, is arranged to control and energize a program-control relay PCR, as hereinafter described.

50 The contacts of the relays RS, RL and RN are arranged in series electrical relation to each other and to the brushes 25 and 26 of the program-control sector RC and the coil of the program-control relay PCR. If a vehicle passes over any one or more of the light-sensitive devices, the resistance between the anode and the cathode of the light-sensitive cell builds up until a discharge 55 no longer takes place, and the difference of potential existing between the anode and the cathode of the light-sensitive cell causes a difference of potential to exist between the control electrode 5 and the anode of the grid-glow tube T, thereby causing a discharge between the anode and the cathode of the grid-glow tube to cease 60 at the first zero-potential point in the alternating-current cycle. For example, suppose that a vehicle passes over the light-sensitive cell CS, the deenergization of the cell and the tube breaks 65 the circuit which includes the corresponding relay RS, thus deenergizing the relay and permitting the contacts to open. Normally, the relay PCR, which, on closing, energizes the program-control motor, is held in its energized or open 70 position by reason of the electrical circuit, which

75 may be termed the relay circuit, including main-line conductor L2, conductor 21, the contacts of relay RS, conductor 22, the contacts of relay RL, conductor 23, the contacts of relay RN, conductor 24, brush 25, sector 27, brush 26, conductor 28, the coil of the relay PCR, conductor 29 and main-line conductor L1.

When the sector 27 of the relay controller 8 is under the brushes 25 and 26 in its normal position, the brush 9 of the signal control 11 makes 10 electrical contact with sector 31, and an electrical circuit is provided for energizing the "main green" signal MG, which includes main-line conductor L1, conductor 30, the brush 9 of the signal controller, sector 31, conductor 32, the 15 lamp of the "main green" signal MG, conductor 33 and main-line conductor L2.

20 The breaking of the relay circuit by the "dropping out" of any one of the relays RS, RL or RN, because of the passage of a vehicle, deenergizes the coil of the program-control relay PCR and causes a circuit to be established including the main-line conductor L1, conductor 34, the contacts of the program-control relay PCR, conductor 35, the program-controller motor PCM, 25 conductor 36 and main-line conductor L2, thus causing the program-control motor to become energized, and the controller disc 8 and brush 9 of the signal controller 11 to rotate to effect a 30 cycle of sequential operation of the "stop, caution" and "go" signals as hereinafter described.

35 After the brush 9 has rotated until it has lost contact with the sector controlling the signal MG, thus deenergizing it, contact is established with sector 37 and the yellow signal Y is energized by means of the circuit including conductors L1 and 30, brush 9, sector 37, conductor 38, signal Y and conductor 33.

40 On further rotation of the brush, the circuit through the signal Y is broken, and a circuit is established through main-line conductor L1, conductor 39, brush 9, sector 39, conductor 41, signal MR, conductor 33 and main-line conductor L2, to energize the MR signal to indicate red or 45 "stop" on the main highway and green or "go" on the auxiliary highway. The vehicle standing in the auxiliary traffic lanes or on the left-hand-turn lane may now cross or enter into the main highway. The brush of the signal control PC continues to rotate and deenergizes the circuit including the signal MR and again energizes the signal Y. On further rotation, the brush deenergizes the signal Y and energizes the signal MG. Meanwhile, if no other vehicles have approached on the auxiliary highway or are in the 50 left-hand-turn lane, the relays RS, RL, RN are all in their closed or energized position and, when sector 27 makes contact with brushes 25 and 26, the relay control circuit is reestablished through the program-control relay PCR, causing the coil 55 to be energized and the contacts to become disengaged to stop the program-control motor.

60 The relay RL is preferably provided with a device known to the art which causes the relay to open after a certain predetermined length of time but is provided with an automatic reset feature which causes the relay to return fully to its energized position if only a portion of the time has elapsed. In this way, successive vehicles passing over the relay may not add their times to cause the relay eventually to function, but, if a single vehicle stops over the relay the required length of time, its contacts become disengaged to actuate the change of signals.

As used herein the terms "lane", "highway", and "thoroughfare" are defined as follows:

A "lane" is a single traffic path along which traffic flows in one direction only.

5 A "highway" embraces a plurality of traffic paths along at least one of which traffic flows in a direction opposite to the direction of traffic flow along the others.

10 "Thoroughfare" is generic to both "lane" and "highway" and means either one or the other. A "thoroughfare" may also embrace two or more lanes in which traffic flows in the same direction.

15 Although I have described a specific embodiment of my invention, it is apparent that changes may be made therein without departing from the spirit and scope of my invention, as set forth in the appended claims.

I claim as my invention:

1. A traffic control system for two substantially parallel and opposite traffic lanes, comprising a "stop" signal for each lane, means so disposed as to be actuated only by a unit of traffic in one lane taking a position to make a turn across the other lane and not by through traffic in said one lane and means, to be actuated by said traffic-actuable means when said traffic-actuable means is actuated, for actuating a stop signal for said other lane.

2. A traffic control system for a plurality of 30 intersecting highways comprising stop and go indications to be displayed for said highways, stop indications to be normally displayed for one of said highways and go indications to be normally displayed for another of said highways, 35 means for so varying the display of said indications that go indications are displayed for said first-named highway and stop indications are displayed for said last-named highway and means, to be actuated by vehicles moving along 40 said last-named highway and desiring to make a left-turn on the display of a stop indication for said last-named highway, for activating said varying means to vary the display of said indications, said means including timing means to 45 cooperate with said varying means to prevent the activation of said varying means by said vehicle-responsive means unless said vehicle-responsive means has been actuated continuously for a predetermined interval of time which is appreciably longer than the interval during which 50 said vehicle-responsive means is activated by a vehicle moving along said last named highway at a normal rate, thereby to prevent activation of said varying means by the actuation of said vehicle-responsive means by said last-named vehicles.

55 3. A traffic control system for the intersection of a thoroughfare and a highway comprising stop and go indications to be displayed for said highway, go indications displayed for said highway, means for so varying the display of said indications that stop indications are displayed for said highway and means, to be actuated by vehicles moving along said highway and desiring to make a left turn into said thoroughfare on the display of a stop indication for said highway, for activating said varying means to vary the display of said indications as aforesaid, said means including timing means to cooperate with said varying means to prevent the activation of said varying means unless said vehicle-responsive means has been actuated continuously for a predetermined interval of time which is appreciably longer than the interval during which said vehicle-responsive means is activated by vehicles moving along said highway at a normal rate,

thereby to prevent activation of said varying means by the actuation of said vehicle-responsive means by said last-named vehicles.

4. A traffic control system for a plurality of lanes including a first lane and a second lane 5 comprising stop and go indications to be displayed for said first lane, go indications to be at times displayed for said first lane, means, when activated, for so varying the display of said indications that stop indications are displayed for 10 said first lane and means, to be vehicle actuated, by vehicles moving along said second lane for activating said varying means, said vehicle-actuated means including timing means to permit the activation of said varying means only after said 15 vehicle-actuated means is continuously actuated for a predetermined interval of time that is appreciably longer than the interval during which a vehicle moving along said second lane at a normal rate actuates said vehicle-responsive means 20 thereby to prevent the variation of said indications by the coaction of said vehicle-responsive means and the last-named vehicles, said varying means being so activated, even if said vehicle-actuated means is being actuated by a vehicle, 25 that it is capable of effecting the display of a stop indication for said first lane while said vehicle-actuated means continues to be actuated by said vehicle.

5. Traffic control apparatus for interfering 30 traffic lanes including signalling means for said lanes to interrupt right of way to traffic moving in one of said lanes, means to be actuated by vehicles in another of said lanes, and means responsive to actuation of said vehicle-actuable 35 means for causing said signalling means to interrupt right of way to traffic in the first said lane, the last said means including selecting means by the operation of which said responsive 40 means operates said signalling means only when said vehicle-actuable means is actuated by a vehicle continuously for at least a predetermined interval of time which is greater than the interval of time during which it would be actuated by a vehicle moving at a normal rate of speed along 45 said lane and even if said vehicle actuable means continues to be actuated by said vehicle.

6. A traffic control system for two substantially parallel and opposite traffic lanes, comprising a "stop" signal for one of said lanes, means 50 disposed as to be actuated only by a unit of traffic in the other of said lanes taking a position to make a turn across the said first-named lane and not by through traffic in said other lane and means, to be actuated by said traffic-actuable 55 means when said traffic-actuable means is actuated, for actuating said stop signal for said first-named lane.

7. A traffic control system for the intersection of a thoroughfare and a highway comprising stop and go indications to be displayed for one lane of said highway and for said thoroughfare, stop indications to be normally displayed for said thoroughfare and go indications to be normally 60 displayed for said lane, means for so varying the display of said indications that go indications are displayed for said thoroughfare and stop indications are displayed for said lane, and means, to be actuated by vehicles moving along said highway in another lane and desiring to make a left 65 turn across said first-named lane on the display of a stop indication for said lane, for actuating said varying means to vary the display of said indications as aforesaid, said vehicle actuable means including timing means to cooperate with 70

said varying means to prevent the actuation of said varying means by said vehicle-responsive means unless said vehicle-responsive means has been actuated continuously for a predetermined 5
5 interval of time which is appreciably longer than the interval during which said vehicle-responsive means is actuated by a vehicle moving along said highway at a normal rate, thereby to prevent actuation of said varying means by the actuation 10
10 of said vehicle-responsive means by said last-named vehicles.

8. A traffic control system for the intersection of a thoroughfare and a highway comprising stop and go indications to be displayed for one lane of 15
15 said highway, go indications to be normally displayed for said lane, means for so varying the display of said indications that stop indications are displayed for said lane, and means, to be actuated by vehicles moving along said highway in

another lane and desiring to make a left turn across said first-named lane on the display of a stop indication for said lane, for actuating said varying means to vary the display of said indications as aforesaid, said vehicle actuatable means including timing means to cooperate with said varying means to prevent the actuation of said varying means by said vehicle-responsive means unless said vehicle-responsive means has been actuated continuously for a predetermined interval of time which is appreciably longer than the interval during which said vehicle-responsive means is actuated by a vehicle moving along said highway at a normal rate, thereby to prevent actuation of said varying means by the actuation 15
15 of said vehicle-responsive means by said last-named vehicles.

PHILLIPS THOMAS.
